UNITED STATES PATENT OFFICE.

CARL F. BRANDENBERGER, OF FORT MADISON, IOWA.

PUMP.

Application filed June 11, 1920. Serial No. 388,298.

To all whom it may concern:

Be it known that I, CARL F. BRANDENBERGER, a citizen of the United States, residing at Fort Madison, in the county of Lee 5 and State of Iowa, have invented a new and useful Pump, of which the following is a specification.

It is the object of this invention to provide a pump which may be so constructed that it 10 will operate without packing boxes, there being no loss of water whilst the pump is in operation.

Another object of the invention is to provide novel means whereby the water will be 15 permitted to drain down, so that the pump cannot freeze.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from the 30 spirit of the invention.

In the accompanying drawings:—

Figure 1 is a diagram showing a pump constructed in accordance with the invention; Figure 2 is a side elevation showing the cylinders and attendant parts, portions being broken away; Figure 3 is a cross section on the line 3—3 of Figure 2; Figure 4 is an elevation showing the pistons, parts being broken away; Figures 5 and 6 are sectional details showing the valves at the respective ends of the piston rod; Figure 7 is a cross section on the line 7—7 of Figure 2; and Figure 8 is a diagram showing a slightly modified form of the invention.

In carrying out the invention, connected vertically aligned cylinders 1 and 2 are provided, the cylinder 1 being slightly larger in diameter than the cylinder 2, the cylinder 2 having a foot 3 and the cylinder 1 being 50 provided with a cap 4 retaining a disk 5 having an opening 6 controlled by a downwardly closing check valve 7 located in the cap 4. The cylinders 1 and 2 have transverse extensions defining a lateral chamber 8, the inlet of which is provided with a screen 9. A pipe 10 is connected to the cap 4, the 55 upper end of the pipe communicating with a valve seat 20 located at the lower end of an air chamber 17. A valve 21, which may be a ball valve, is located in the air chamber 17 and is adapted to cooperate with the seat 20, upward movement of the valve being limited, if desired, by a stop 22 in the air chamber. A pipe 18 is provided, the lower end 19 of the pipe extending downwardly into the 60 upper end of the air chamber 17, so that air can accumulate in the upper end of the chamber and effect a continuous flow from the pipe 18, the pipe being provided with an outlet 12. The pipe 18 is carried by a base 11. 65 A bypass 14 communicates at its lower end with the cylinder 2 adjacent to the lower end of the bypass communicating with the pipe 10 immediately above the cylinder 1 and below 70 the air chamber 16. A downwardly closing check valve 15 is interposed in the bypass 14 and is located closely adjacent to the cylinder 2, the check valve having a minute bleed port 16. A cut-off valve 23 is located 75 in the pipe 18 between the air chamber 17 and the outlet 12 and may be manipulated in any suitable way, for instance, by means of an arm 24 and an operating member 25, the operating member being slidably mount- 80 ed in the base 11.

A rod 26 is located in the cylinders 1 and 2 and carries an upper piston 27 operating in the cylinder 1. As indicated in Figure 5, the upper piston 27 may include a tubular body 28 having a shoulder 29 and a neck 30. A spider 31 is threaded on the neck 30, a washer 32 being bound between the spider and the shoulder. An upwardly opening valve 33 controls the passage of liquid downwardly through the tubular body 29 and is located within the spider 31. On the lower end of the rod 26 there is a lower piston 46, shown in detail in Figure 6. The piston 46 includes a tubular body 34 having a shoulder 35 and a depending neck 36. A spider 37 is threaded on the neck 36, a ring 38 and a washer 39 being interposed between the end of the spider and the shoulder 35. A valve 40 operates in the spider 37 and controls a 100 passage of liquid upwardly through the member 34, the valve preferably including a cork body 41 on the upper end of which is a top piece 42 of leather or the like, the parts 41 and 42 being held together by a securing element 43. A tube 44, of small diameter, passes through the bars 41 and 42,

and constitutes a bleed port. A hollow cap 45 is mounted in the upper end of the body 34 and has side openings 47, the lower end of the rod 26 being connected to the cap. 5 The rod 26 has an offset arm 48 slidably mounted in the upper portion of the chamber 8 and mounted slidably, if desired, in the base 11. The upper end of the arm 48 may be connected in any suitable way, as indicated at 49 to an operating means 50 of any desired sort.

Assuming that the cylinders 1 and 2 are submerged to about the level indicated at 51 the water will enter the space between 15 the pistons 27 and 46, by way of the inlet 9 and the lateral chamber 8. On the up-stroke, the valve 33 will close, the valve 40 will open, and the check valve 15 will close due to the head of water upon it. When 20 the valve 40 opens, the water which is between the pistons 27 and 46 will flow downwardly into the space in the cylinder 2 below the piston 46. The water in the cylinder 1 will be raised by the piston 27 and will 25 traverse the pipe 10, the air chamber 17, the pipe 18 and its outlet 22. On the down stroke, the valve 33 will open, permitting the water in the space between the pistons 27 and 46 to flow into the space in the cylinder 30 1 above the piston 27. The valve 40 closes, and water below the piston 46 is forced out of the lower portion of the cylinder 2 through the bypass 14, the check valve 15 opening, and the water from the bypass 14 35 passing into the pipe 10 and the cylinder 1 above the piston 27.

The air chamber 17 affords a steady flow of water. When the pump is at rest, the water drains downwardly through the pipe 40 10 to a point below the frost line indicated at 52, the water flowing downwardly through the bypass 14 through the bleed port 16 in the check valve 15, into the lower portion of the cylinder 2, and upwardly through 45 the bypass 44 in the valve 40, assuming that the valve is seated, which may be the case because the valve 40 is buoyant. The buoyant valve 21 follows the descending column of water and, ultimately cooperates with the 50 seat 20, to hold the water at a head, below the seat 20. If desired, the valve 23 may be closed by the operating mechanism 24-25, to prevent a downward draining of the water in the pipes 10 and 18 and in the 55 air chamber 17.

It will be observed that the construction of the device is such that when the pumping cylinders are submerged, there is no occasion for packing glands or the like about 60 the rod 48 at the point where it works into the chamber 8. The water, further, is permitted to drain below the frost line and the chance of freezing is reduced to a minimum.

In the modification shown in Figure 8, parts hereinbefore described have been 65 designated by numerals previously used with the suffix "a". In this form of the invention, the air chamber 17 may be omitted if desired. The relatively short inlet screen 9 of Figure 2 is replaced by a longer inlet 53, 70 the lower end of which constitutes a cylinder 54. At the lower end of the cylinder 54 there is a foot valve 55. A casing 56 communicates with the upper end of the laterally enlarged chamber 8^a. A rod 57 operates in the parts 56, 8^a, 53 and 54 and carries a piston 58 working in the cylinder 54. This form of the invention is adapted to be used when it is not convenient to submerge the pumping cylinders, the water 80 level standing, for instance, at the level indicated at 75 in Figure 8. The piston 58 delivers the water upwardly into the lateral chamber 8^a, and thereafter, the operation of the device is practically the same 85 as that set forth in connection with the form shown in Figure 1. The water may be permitted to drain downwardly out of the pipe 10^a into a connection 59, and from the connection 59 into the casing 56, and if the 90 water level rises sufficiently in the casing 56, the water can flow out of the casing by way of an outlet 60.

Having thus described the invention, what is claimed is:—

In a device of the class described, communicating, aligned upper and lower cylinders having a lateral chamber provided at its lower end with an inlet; a discharge pipe leading upwardly from the top of the upper cylinder; an air chamber in the pipe; a downwardly closing check valve in the air chamber; a cut-off valve in the pipe and located above the air chamber and under the control of an operator; pistons in the cylinders; a connection between the pistons and having an operating means extended laterally into the chamber and upwardly out of the top of the chamber; an upwardly opening valve in the piston of the upper cylinder; a buoyant upwardly closing valve in the piston of the lower cylinder; a downwardly closing check valve at the upper end of the upper cylinder; a by-pass connected to the pipe above the last specified check 110 valve and connected to the lower cylinder adjacent to the lower end thereof; and a check valve in the by-pass.

In testimony that I claim the foregoing as my own, I have hereto affixed my signature 120 in the presence of two witnesses.

CARL F. BRANDENBERGER.
